UNITED STATES PATENT OFFICE.

JAMES INGLIS, OF TORONTO, ONTARIO, CANADA; F. DUNDAS TODD, ADMINISTRATOR OF SAID INGLIS, DECEASED, ASSIGNOR, BY MESNE ASSIGNMENTS, TO GEORGE R. LAWRENCE, OF CHICAGO, ILLINOIS.

PHOTOGRAPHIC FLASH-LAMP.

No. 873,242.

Specification of Letters Patent.

Patented Dec. 10, 1907.

Application filed June 24, 1904, Serial No. 214,001. Renewed October 29, 1906. Serial No. 341,200.

To all whom it may concern.

Be it known that I, JAMES INGLIS, of the city of Toronto, in the county of York, in the Province of Ontario, Canada, have invented 5 certain new and useful Improvements in Photographic Flash-Lamps, of which the following is a specification.

My invention relates to improvements in photographic flash lamps, and the object of 10 the invention is to devise a lamp and hood therefor, which will enable a photographer to take a flash-light picture without allowing the smoke from the burned flash-powder to escape into the room and at the same time 15 to soften the light from the flash so as to produce a soft and artistic negative.

A further object is to so construct said hood that the walls may yield freely to the concus- 20 sion of the explosion, while a portion of the contained air is permitted to escape, as well as to render the hood fire-proof so that the igni- 25 tion may be made directly therein without the intervention of other protective features and without danger of igniting the hood,— 25 all of which is hereinafter more particularly described and definitely pointed out in the claims.

In the drawings, Figure 1, is a perspective view of my improved hood, showing novel 30 means for suspending the same as well as means for supporting a flash-lamp therein, Fig. 2, is a central vertical sectional view of the hood and supporting standard, Fig. 3, is a perspective view of the essential features of 35 the flash-lamp, and Fig. 4, is a detail of a detachable connection between the lower portion of the hood support and that which connects with the hood.

Corresponding letters of reference in the 40 different figures indicate like parts.

Referring to the drawings, 1, Figs. 1 and 2, represents a hood or bag formed from canvas or other suitable flexible fabric or material, said hood being closed upon the sides 45 and at the top, but preferably arranged to be normally open at the bottom, a draw-string 2, or other suitable means, being provided for closing it. In the instance illustrated, said bag is represented as being rectangular 50 in form although it is obvious that its shape may be varied indefinitely. The front of the bag is by preference made partially or wholly transparent or translucent. This may be accom- 55 plished either by constructing the same from tracing cloth or by making it of thinner

or lighter material than that of the other parts, although it is manifest that the entire body may be the same throughout.

Inasmuch as my invention contemplates the ignition of the flash-light material directly 60 within the bag, without the intervention of any supplemental casing or special ignition chamber or shield, it is essential that said bag should be rendered fire-proof. This may be accomplished by treating the fabric with sul- 65 fid of barium, or other suitable fire-proofing composition.

The object of having the bag normally open at the bottom is to provide for the escape of air therefrom and to permit the liberated 70 gases to expand when the explosion of the flash-light powder occurs; it being under- 75 stood that the flash being made upwardly towards the closed top causes the gas and smoke to ascend, thereby taking the place of a body of air which is expelled from below.

While it is obvious that the bag may be suspended in any one of various ways, I prefer to provide a light portable support therefor which may be readily folded and trans- 80 ported. In the example shown, I have pro- 85 vided as a main support, a tube 3, upon which is mounted a sliding ring 4, to which is jointedly attached by means of screws or pins 5, legs 6, which are jointedly connected 85 with a ring 7 upon the lower part of the main standard by means of braces 8. The ring may be adjusted and secured in any desired position and when moved to the top, the legs are caused to fold compactly against the 90 standard. Telescoping sections 9, 10, are fitted within the main tube 3 and secured at any desired height by means of set-screws 11 and 12.

Inasmuch as it is desirable to have the sup- 95 porting structure very light, I have con- 100 structed it so that the tripod may stand cen- trally beneath the hood. I accomplish this result by attaching an arm 13 to the top of the section 10, extending it rearwardly to the back of the main body of the bag and rigidly connecting to its rear end a short vertical portion 14 having a reduced part 15 which is adapted to enter the lower end of a tubular section 16. The latter is arranged to ex- 105 tend above the top of the bag, and is pro- 110 vided with a notch 17 in its lower end adapt- ed to engage a pin 18 to prevent the section from turning. A horizontal arm 19 is pro- 115 vided with a pintle 20, which is fitted to enter

the upper end of the tube 16, so as to hold said arm rigidly in position. Hooks 21, 21, are attached to the arm 16 and adapted to pass through the hood and engage bars 22, 5 22, for the purpose of suspending said hood in an expanded position.

I prefer to provide a recess for the reception of the standard and horizontal arm 13 by extending the lower and rear portion of 10 the bag inwardly as shown, and in connection therewith, in order to properly distend the bag, I secure therein a horizontal cross-bar 23, to the middle of which is attached a ring 24, adapted to be connected with the part 14 15 by means of a hook 25.

An elongated opening 26 is formed in the back of the hood in which is secured a frame-plate 27 having an opening therein provided with a hinged covering flap 28. A tray or 20 flash pan 29 formed from sheet-metal is adapted to fit within the opening 26, said tray being provided with a rear flange 29^a to close said opening. A bracket 30 is rigidly attached to the rear of the tray and is provided 25 with a clip 31 for securing the tray to the bar 16. Said bracket is preferably U-shaped as shown and is arranged to support a lamp reservoir 32 having a burner 33 immediately above and in the depressed portion of the 30 bracket. An ignition tube 34 is extended through the front portion of the bracket with its forward open end in the tray. An opening in the rear portion of the bracket is connected with a flexible tube 35, having the 35 usual air bulb 36 upon the end.

The operation of said device is as follows: The hood being suspended as shown, the lamp is lighted, the flash-light powder placed in the tray and the latter secured in position 40 in the opening 26. The pressure of the bulb causes the flame to be blown through the igniting tube, thereby igniting the powder. The explosion causes the displaced air to be discharged through the bottom opening 45 while the smoke remains in the bag. The bottom may then be closed, the lamp removed, and the smoke discharged in the open air when the operation may be repeated.

Having thus described my invention, I 50 claim:

1. In a flash-lamp, the combination with the lamp and the supporting standard, of a hood of flexible fire-proof material having an opening in the back thereof, the tray of the 55 flash-lamp secured to said standard and extending through said opening, and an open bottom provided with means for collapsing the same, substantially as described.

2. In a flash light apparatus, the combina-

tion of a bag made of flexible material, a portion of said bag at least being translucent, means for supporting said bag with a portion thereof collapsed so as to permit the bag to expand under internal pressure, means for supporting a flash light charge within said 65 bag, and means for igniting said charge.

3. In a flash light apparatus, the combination of a bag composed wholly of a flexible material, a portion of said bag at least being translucent, means for supporting said bag 70 in a partially expanded condition so as to permit it to expand further under internal pressure, means for supporting a flash light charge within said bag, and means for igniting said charge.

4. In a flash light apparatus, the combination of a bag composed wholly of a flexible fire proof fabric a portion of which at least is translucent, of means for supporting said bag in a partially expanded condition so as 80 to permit it to expand further under internal pressure, means for supporting a flash light charge within said bag, and means for igniting said charge.

5. In a flash light apparatus, a bag composed wholly of a flexible fire-proof material, a portion of the bag at least being translucent, means for loosely supporting said bag in an expanded condition which permits the bag to expand further under internal pressure, 90 means for supporting a flash light charge within said bag, and means for igniting said charge.

6. In a flash light apparatus, the combination with a bag open at one end and composed of a flexible fire-proof material, a portion of which at least is translucent, of means for yieldingly supporting said bag in an expanded condition so as to permit it to expand further under internal pressure, the mouth 100 of the bag being at the bottom, of means for supporting a charge of flash light material within said bag, means for igniting said charge, and means for closing the mouth of the bag.

7. In a flash light apparatus, the combination with a collapsible fire proof receptacle a portion of which at least is translucent, means for supporting said receptacle in an expanded condition which permits it to expand further under internal pressure, means for supporting a flash light charge within said receptacle, and means for igniting said charge.

JAMES INGLIS.
